UNITED STATES PATENT OFFICE.

ALEXANDER HALLENBECK, OF COBLESKILL, NEW YORK.

WAGON-SEAT CORNER-IRON.

SPECIFICATION forming part of Letters Patent No. 245,162, dated August 2, 1881.

Application filed December 30, 1880. (Model.)

To all whom it may concern:

Be it known that I, ALEXANDER HALLENBECK, of Cobleskill, in the county of Schoharie and State of New York, have invented a new and Improved Wagon-Seat Corner-Iron, of which the following is a specification.

The object of this invention is to prevent the opening of the joints at the junction of the back and ends of a wagon-seat.

10 The invention consists of an angle-iron plate having an inclined end piece to fit on the bottom of the wagon-seat, and having a rib or web extending along its back, on each side of which, at its edge, is a flange set thereon at an angle of about forty-five degrees, the two flanges forming a V-shaped anchoring-piece that is designed to be entered into corresponding grooves in the back and ends of the seat, where they are jointed together.

20 Figure 1 is a perspective view of the device in position on a wagon-seat. Fig. 2 is a side elevation of the corner-iron. Fig. 3 is a cross-section of the corner-iron on line *xx*, Fig. 2.

Similar letters of reference indicate corresponding parts.

25 In the drawings, *A* represents a wagon-seat, of which *a* is the back, *b* an end, and *c* the bottom. At the junction of the back *a* and end *b* the said back *a* and end *b* are vertically grooved, as shown at *d*.

30 *B* represents the corner-iron, consisting of the front plate, *f*, formed into an angle to fit into the corner made by the junction of the back *a* and end *b*, and having its sides or wings extended onto said back *a* and end *b*, and there secured by screws *g*. The end piece, *h*, of said corner-iron *B* is of quadrantal shape and fits

upon the seat *c*, and is there fastened by a screw, *g*. The rib or web *k* is entered in the joint between the back *a* and end *b*, and the flanges *l* are fitted into the grooves *d*, as shown, so that said flanges *l* extend parallel with the faces of back *a* and end *b* respectively, whereby said wagon-seat *A* is firmly held together at the corner in a strong and durable manner.

The flanges *l* are cut away along their edges, as shown at *m*, to detract from their weight, and at the same time to obviate the necessity of cutting grooves *d* of continuous width, and thereby unnecessarily weakening the said back and ends *a b*.

I am aware that corner-plates have been constructed so that the back ends may be dovetailed; but this makes the proper joining extremely difficult; also, that they have been constructed to necessitate a joint on the outside of seat, which is very objectionable. I construct my plates so as to have a miter-joint in the corner and to have the V-shaped iron inclose the joint, the iron entering the wood sidewise.

What I claim as new and of my invention is—

As an improved article of manufacture, a wagon-seat corner-iron constructed substantially as herein shown and described, consisting of front angle-plate, *f*, provided with end piece, *h*, web *k*, and flanges *l*, arranged as set forth.

ALEXANDER HALLENBECK.
